(57) CLAIM

I claim the ornamental design for a jersey, as shown and described.

DESCRIPTION

FIG. 1 is a perspective view of a jersey, showing my new design;

FIG. 2 is an enlarged perspective view of the claimed region of FIG. 1;

FIG. 3 is a front view thereof; and,

FIG. 4 is a right side perspective view thereof.

The broken lines illustrating the wavy boundary of FIGS. 2-4 represent boundaries of the enlarged views. The remaining broken lines illustrating the jersey represent portions of the article that form no part of the claimed design.
